Application February 24, 1940, Serial No. 320,696

11 Claims. (Cl. 271—79)

This invention relates to printing presses or similar machines, and more particularly to sheet handling devices associated with such machines and means for moving these devices from operative positions with respect to the machine to displaced positions, so that access may be readily had to parts of the machine normally concealed or obstructed by the sheet handling devices.

The general purpose of the present invention is to provide a novel device of this character of improved construction and operation, which may be applied to a wide variety of sheet treating machines, but which probably finds its greatest utility and adaptation in connection with the sheet feeding or delivery mechanism of flat bed printing presses of the general bed and cylinder type.

In its preferred embodiment, such as that illustrated and described in the present application, the invention contemplates the provision of sheet delivery devices for a flat bed press which comprise an auxiliary delivery pile carrying frame pivotally connected to the press frame for swinging movement in a horizontal plane, and a normally horizontally disposed delivery conveyor frame which is also pivotally attached to the press frame but is disposed upon a horizontal pivot for vertical swinging movement to a raised position to provide access to the form bed. The horizontally swinging pile carrying frame and the vertically swinging conveyor frame are operatively connected by mechanism which insures simultaneous movement of these frames to and from their operative and displaced positions.

Another object of the invention is the provision, in these operative connections, of counter-balancing means for the frame which is to be lifted against the force of gravity. A still further object is the provision of means for retaining the frames in their extreme positions in either direction.

Other objects and features of novelty will be apparent from the following specification when read in connection with the accompanying drawings in which one embodiment of the invention is illustrated by way of example.

In the drawings.

Figure 1 is a view in side elevation of the delivery end of a printing press embodying the principles of the invention, the auxiliary frames being in closed or operative position;

Figure 2 is a view in end elevation of the delivery portion of the press;

Figure 3 is a fragmentary horizontal sectional view taken on line 3—3 of Figure 1; and

Figure 4 is a view in side elevation on a reduced scale showing the auxiliary frames opened up to provide access to the form bed.

The flat bed press to which the delivery mech-

anism is applied, and a portion of which is shown in the drawings, comprises the main supporting frame 10 upon which is mounted the impression cylinder, diagrammatically indicated at 11, and the horizontally reciprocating form bed suggested at 12. At one of its extreme positions of movement the form bed occupies a portion of the space indicated at 12' adjacent the delivery end of the press frame 10.

An auxiliary delivery pile carrying frame is shown at 14. This frame 14 is of a generally inverted L-shape, the upper portion of which overhangs the delivery pile P which is disposed upon the platform 15, which is in turn supported by the tines 16 pivotally carried as at 17 by the vertically movable carriage 18. The carriage 18 extends across the frame from one side to the other and at each side is provided with the inner rollers 19 and outer rollers 20 which embrace a flange 21 which serves to guide the carriage in its vertical movement. A chain hoist 25 is provided for raising and lowering the pile-carrying carriage, the parallel chains of the hoist being trained over the upper sprockets 26 and the lower sprockets 27, and being secured at their ends to the carriage 18 as at 28 and 29 respectively. The upper sprockets 26 are mounted on a transverse shaft 30 which may be rotated by any suitable mechanism, and the lower sprockets 27 are carried by the vertical rods 32 which pass through the brackets 33 and 34 of the frame 14 and are adjustably or resiliently mounted therein.

The pile supporting frame 14 is pivotally carried by the main press frame 10 by means of the following arrangements. As clearly shown in Figures 1, 2, and 3 of the drawings, there are formed at one side of the auxiliary frame 14 the laterally and forwardly projecting spaced hinge members 36, which are both secured to the pintle shaft 38, this shaft being mounted in suitable bearings in one of the side frame portions of the main frame 10. In order to aid in the anti-frictional support of the pivotal auxiliary frame 14, ball bearing assemblies 40 are interposed between portions of the main frame 10 and the hinge members 36. Thus it will be seen that the frame 14 may be swung about the axis of the pintle shaft 38 from the position shown in Figure 1 of the drawings, where it is in abutment with the end of the main frame 10, to the open position shown in Figure 4, where the auxiliary frame is disposed at right angles to the main frame.

In order to deliver the printed sheets from the impression cylinder 11 of the press to the pile P supported by the frame 14, there is provided a delivery conveyor which may be of any suitable type, but which in the present exemplary embodiment comprises a chain gripper conveyor having two parallel sets of chains 45 which are

trained around the pairs of sprocket wheels 46 mounted at each end of the conveyor upon transverse shafts 47. Gripper members indicated very diagrammatically at 48 may be disposed at intervals along the chains 45 for the purpose of seizing the sheets as they are released from the impression cylinder grippers and transporting them to a position directly above the delivery pile P whereupon they are released and allowed to fall upon the pile. The delivery conveyor is carried by the normally horizontally disposed frame 50 which is pivoted coaxially with the inner conveyor shaft 47 to the upper side frames of the press adjacent the impression cylinder. The outer portion of the frame 50 is adapted to rest upon the upper overhanging portion of the inverted L-shaped auxiliary frame 14.

When access to the form bed 12 is desired, the frame 50 is raised about its pivot to the position shown in Figure 4 of the drawings, and in this figure it will be seen that both of the frames 14 and 50 are disposed in their displaced positions so that access to the bed of the press is readily obtained.

In accordance with the provisions of the invention, means are provided for interconnecting the two delivery frames for simultaneous movement to and from their operative and displaced positions. As more readily observed in Figures 2 and 3 of the drawings, the rotating pintle shaft 38 is provided with a bevel gear 55 which meshes with another bevel gear 56 carried by the transverse shaft 60 mounted in suitable bearings carried by the main press frame 10. Rigidly secured to this transverse shaft 60 adjacent each side of the press are the brackets 62 which comprise crank arms adapted to be oscillated by rotation of the rock shaft 60. Pivotedly connected to the ends 63 of these cranks 62 and extending upwardly therefrom are the links 64, the upper ends of which are pivotally connected as at 65 with each side of the delivery conveyor frame 50. It will be readily understood that when the frame 14 is swung horizontally from the position shown in Figure 1 through an angle of ninety degrees to the position shown in Figure 4, the shaft 38 and the inter-geared shaft 60 will each rotate through a corresponding angle of ninety degrees. Consequently, the brackets 62 will swing through a similar angle and, through the links 64, the conveyor frame 50 will be raised sufficiently to provide access to the bed at the same time that the pile carrying frame 14 is swung aside.

Counterbalancing means are provided for neutralizing the weight of the frame 50 and aiding in the simultaneous swinging of the two frames. Each of the crank brackets 62 are provided with offset portions 70 to which is pivotally connected as at 71 the upper end of a rod 72. This rod 72 is telescopically received within a tube 74, the lower end of which is pivotally connected to the main frame 10 as at 75. The upper end of the rod 72 and the lower end of the tube 74 are provided with spring seats between which is adapted to be compressed the coil spring 76 which, as clearly seen in the drawings, serves to continually urge the linkage 72, 74 toward extended position and thus serves to bias the cranks 62 toward upper position and counterbalance the weight of the frame 50.

In order to secure the several frames in their closed or operative positions the following devices are provided. Pivotedly mounted upon the vertical portion of the frame 14 as at 80 is a bell crank 81 having a handle 82 at one end and a

hook 83 at the other which is adapted to engage the edge of a slot 84 provided in the end of the main frame 10, when the two frames are in their abutting operative positions as shown in Figure 1.

5 The hook 83 may, of course, be readily released by manipulation of the handle 82 prior to swinging the frame to open position. In order to properly align and retain the frames 50 and 14, a hook 85 is pivoted as at 86 to a portion of the conveyor frame 50 and is adapted to engage a stationary detent 87 secured to the upper portion of the pile supporting frame 14.

Means are also provided for positively supporting the frame 50 when in its open position 15 shown in Figure 4. A depending hook 90 is pivoted to a portion of the press frame 10 as at 91 and is provided with a handle 92. The hook is normally disposed as shown in Figure 1 of the drawings, but when the lower end block 95 of one of the links 64 rises to its upper position it displaces the hook 90 by contact with its bevelled edge, and then when it passes the end thereof the hook moves beneath the block 95 and serves to positively support the link 64 and thus the 25 raised conveyor frame 50. When it is desired to close the frames the handle 92 is employed to swing the hook from beneath the element 95. Similar hooks may be provided upon both sides of the press if desired.

30 By means of the present invention, the displacement of the delivery mechanism of printing presses and similar machines may be greatly facilitated and the efficiency of operation increased especially in connection with preparing 35 the form for the printing operation and the inspection, adjustment, and removal thereof at any time.

It is understood that various changes and modifications may be made in the embodiment 40 illustrated and described herein without departing from the scope of the invention as defined by the following claims.

Having thus described the invention, what is 45 claimed as new and desired to be secured by Letters Patent is:

1. In a printing press or the like, in combination, a main frame, a sheet delivery frame pivoted to said main frame for horizontal swinging movement to and from operative position, a conveyor for transferring printed sheets from said press, a supporting frame for said conveyor pivoted to said main frame for vertical swinging movement to and from operative position, and means operatively connecting said delivery frame 50 and said conveyor frame for causing the latter to move to and from operative position simultaneously with said delivery frame.

2. In a printing press or the like, in combination, a main frame, a sheet delivery frame pivoted to said main frame for horizontal swinging movement to and from operative position, a conveyor for transferring printed sheets from said press, a supporting frame for said conveyor pivoted to said main frame for vertical swinging movement to and from operative position, and positive drive means connecting said delivery and conveyor frames for effecting the described movements of one of said frames in response to corresponding movements of the other.

70 3. In a printing press or the like, in combination, a main frame, a sheet delivery frame pivoted to said main frame for horizontal swinging movement to and from operative position, a conveyor for transferring printed sheets from said press, a supporting frame for said conveyor piv-

oted to said main frame for vertical swinging movement to and from operative position, and positive drive means connecting said delivery and conveyor frames for effecting the described movements of one of said frames in response to corresponding movements of the other, said last named means comprising a toothed element associated with said delivery frame, a second toothed element meshing with said first toothed element and journaled on said main frame, and linkage means connecting said second toothed element and said conveyor frame.

4. In a printing press or the like, in combination, a main frame, a sheet delivery frame pivoted to said main frame for horizontal swinging movement to and from operative position, a conveyor for transferring printed sheets from said press, a supporting frame for said conveyor pivoted to said main frame for vertical swinging movement to and from operative position, positive drive means connecting said delivery and conveyor frames for effecting the described movements of one of said frames in response to corresponding movements of the other, said last named means comprising a toothed element associated with said delivery frame, a second toothed element meshing with said first toothed element and journaled on said main frame, linkage means connecting said second toothed element and said conveyor frame, and counterbalancing means for assisting the upward swinging movement of said conveyor frame.

5. In a printing press or the like, in combination, a main frame, a sheet delivery frame pivoted to said main frame for horizontal swinging movement to and from operative position, a conveyor for transferring printed sheets from said press, a supporting frame for said conveyor pivoted to said main frame for vertical swinging movement to and from operative position, positive drive means connecting said delivery and conveyor frames for effecting the described movements of one of said frames in response to corresponding movements of the other, and counterbalancing means for assisting the upward swinging movement of said conveyor frame.

6. In a printing press or the like, in combination, a main frame, a sheet delivery frame pivoted to said main frame for horizontal swinging movement to and from operative position, a conveyor for transferring printed sheets from said press, a supporting frame for said conveyor pivoted to said main frame for vertical swinging movement to and from operative position, means operatively connecting said delivery frame and said conveyor frame for causing the latter to move to and from operative position simultaneously with said delivery frame, and latch means for normally maintaining said delivery and conveyor frames in operative relation to said main frame.

7. In a printing press or the like, in combination, a main frame, a sheet delivery frame pivoted to said main frame for horizontal swinging movement to and from operative position, a conveyor for transferring printed sheets from said press, a supporting frame for said conveyor pivoted to said main frame for vertical swinging movement to and from operative position, means operatively connecting said delivery frame and said conveyor frame for causing the latter to

move to and from operative position simultaneously with said delivery frame, and counterbalancing means for assisting the upward swinging movement of said conveyor frame.

5 8. In a printing press or the like, in combination, a main frame, a sheet delivery frame pivoted to said main frame for horizontal swinging movement to and from operative position, a conveyor for transferring printed sheets from said press, a supporting frame for said conveyor pivoted to said main frame for vertical swinging movement to and from operative position, means operatively connecting said delivery frame and said conveyor frame for causing the latter to move to and from operative position simultaneously with said delivery frame, counterbalancing means for assisting the upward swinging movement of said conveyor frame, and latch means for normally maintaining said delivery and conveyor frames in operative relation to said main frame.

10 9. In a printing press or the like, in combination, a main frame, a sheet pile carrying frame pivoted to said main frame for horizontal swinging movement to and from operative position with relation to the press, a sheet conveyor operatively associated with said press and said pile, and pivotally mounted upon one of said frames for swinging movement to and from operative position for transferring sheets between said press and said pile, and means operatively connecting both of said pivoted frames for insuring their simultaneous movement to and from their respective operative positions.

15 10. In a printing press of the class described, which comprises, a main press frame, a printing couple thereon comprising an impression cylinder and a horizontally reciprocating form bed; the combination of a sheet pile supporting frame disposed at one end of the main press frame, a conveyor carried by said press frame and normally adapted to occupy a substantially horizontal position wherein it extends above said form bed, a horizontal pivot connecting said conveyor with said press frame and a vertical pivot connecting said pile supporting frame with said press frame, and means operatively connecting said pile frame and said conveyor for simultaneous movement, whereby said conveyor is swung upwardly away from the form bed at the same time that the pile frame is swung laterally from said form bed to provide access to said bed.

20 11. In a printing press, in combination, a main frame, a sheet delivery frame pivoted to said main frame for horizontal swinging movement to and from operative position, a conveyor for transferring printed sheets from said press, a supporting frame for said conveyor pivoted to said main frame for vertical swinging movement to and from operative position, and positive drive means connecting said delivery and conveyor frames for simultaneous movement, said last named means comprising a vertical pintle shaft to which said delivery frame is fixed, a horizontal shaft having bearings in the press frame, gearing connecting said shafts for simultaneous and proportional rotation, a crank on said horizontal shaft, and a link connecting said crank with said conveyor frame.
